APPARATUS FOR THE CONTROL OF HIGH-WAY CROSSING SIGNALS

Ronald A. McCann, Swissvale, Pa., assignor to
The Union Switch & Signal Company, Swiss-
vale, Pa., a corporation of Pennsylvania

Application December 31, 1937, Serial No. 182,824

6 Claims. (Cl. 246—130)

My invention relates to apparatus for the control of highway crossing signals, and has for an object the provision of novel and improved apparatus controlled by a train approaching the highway for operating the highway crossing signals.

One feature of my invention is the provision of apparatus governing highway crossing signals without the necessity for insulated track sections or track circuits. Other features of my invention will appear as my specification advances.

I shall describe one form of my invention, and then point out the novel features thereof in claims.

15 The accompanying drawing is a diagrammatic view of a preferred form of apparatus embodying my invention.

Referring to the drawing, reference characters 1 and 1a refer to the rails of a single track railway 20 over which traffic moves in both directions, and which is intersected at grade by a highway, designated as H. Located adjacent the intersection is a highway crossing signal, designated as S, which may be of any well-known type, and which is 25 represented on the drawing as an audible highway crossing signal in the form of a electric bell. It will be understood, of course, that my invention is not restricted to this one form of highway crossing signal.

30 Located at a selected point to one side of the intersection H is a track instrument, designated as C1, which is suitably associated with the stretch of railway. This track instrument and such other track instruments as are mentioned in 35 the specification (all track instruments used being preferably of the same type) may be of the well-known types of track instruments provided with a normally closed contact which is operated to an open position in response to a passing train.

40 For example, the track instrument may be of the microphone type covered by United States Letters Patent No. 1,834,077, issued to A. J. Sorensen, on December 1, 1931; or the mercury contact type covered by United States Letters Patent No. 2- 45 076,928, issued to H. G. Witmer on April 13, 1937.

The location of track instrument C1 is determined by the distance that trains using the railway travel during the operating period of signal S. As track instrument C1 is preferably 50 located at the maximum distance traversed by trains during the warning period, the location of track instrument C1 is dependent upon the maximum train speed and the minimum warning period during which signal S operates. For example, assuming a maximum train speed of 90

miles per hour, or 132 feet per second, and a minimum warning period of, say, 20 seconds, during which period a train will travel 2640 (132×20) feet, track instrument C1 should be located 2640 feet from the intersection H. It is to be understood that my invention is not restricted to the figures selected above, but that any combination of maximum speed and minimum warning period desired is included in the scope of my invention, as well as the selection of any arbitrary 10 point for the location of the track instrument C1.

Located between the highway intersection and track instrument C1 is a second track instrument C2. The location of track instrument C2 in relation to track instrument C1 will be discussed later, 15 as it can best be understood in connection with the operation of my apparatus.

A normally energized relay R1 is controlled by track instrument C1 through a simple circuit including track instrument C1, winding of relay R1, 20 and a battery 22. Similarly, a normally energized relay R2 is controlled by track instrument C2 through a simple circuit including track instrument C2, winding of relay R2, and battery 22.

A normally energized slow releasing directional 25 stick relay R6 is controlled jointly by relays R1 and R2. The stick circuit for relay R6 passes from terminal B of a source of current, such as a battery not shown, through front contact 2 of relay R1, front contact 3 of relay R2, front contact 4 of relay R6, and winding of relay R6, to the other terminal C of the source of current. The pick-up circuit for relay R6 passes from terminal B, through front contact 2 of relay R4, front contact 3 of relay R2, contact 5 of a time element device TE1, and winding of relay R6, to terminal C. Time element device TE1 (and a similar device TE2 referred to hereinafter) may be of any of the usual types of time element devices, especially that type disclosed in the United States application for Letters Patent, Serial No. 119,437, filed January 7, 1937, by H. E. Ashworth, for Thermal relays. Time element device TE1 has a heating element 19 which closes the normally open contact 5 at the expiration of a fixed period, such for example as 10 seconds, after the heating element 19 is energized. The circuit for heating element 19 passes from terminal B, through front contact 2 of relay R1, front contact 3 of relay R2, back contact 4 of relay R6, and heating element 19 40 to terminal C. 45

A track instrument C3 is located adjacent the intersection H and suitably associated with the stretch of railway track so as to be free from actuation by vehicles using the highway. A nor- 55

5 mally energized relay R3 is controlled by track instrument C3 through a simple circuit including track instrument C3, winding of relay R3, and a battery 23. Track instruments C4 and C5 are 10 located on the opposite side of the intersection from track instruments C1 and C2, track instrument C4 controlling normally energized relay R4, track instrument C5 controlling normally energized relay R5, and relays R4 and R5 jointly controlling the normally energized slow releasing directional relay R8 and time element device TE2, by circuits similar to those traced for the control of relays R1, R2 and R6 and time element device TE1 by track instruments C1 and C2. The locations of track instruments C4 and C5 are determined in a manner similar to the determination of the location of track instruments C1 and C2.

20 The apparatus further includes a normally energized stick relay R7. The stick circuit for relay R7 passes from one terminal of a battery 25 through line wire 26, front contact 6 of relay R1, line wire 27, front contact 7 of relay R7, winding of relay R7, line wire 28, front contact 9 of relay R5, and line wire 29 to the 25 other terminal of battery 25. Back contact 10 of relay R6 provides a shunt path around front contact 6 of relay R1, and back contact 11 of relay R8 provides a shunt path around front contact 9 of relay R5 in this stick circuit for 30 relay R7. The pick-up circuit for relay R7 is normally open, and passes from one terminal of battery 25, through line wire 26, front contact 6 of relay R1, line wire 27, back contact 12 of relay R5, winding of relay R7, line wire 28, 35 front contact 9 of relay R5, and line wire 29, to the other terminal of battery 25. The immediate operating circuit for signal S passes from one terminal of battery 25, through line wire 30, winding of signal S, line wire 31, and 40 back contact 13 of relay R7, to the other terminal of battery 25.

45 When no train is within the control stretch, the apparatus is in its normal condition. In this condition, the relays controlled by the associated track instruments are energized, the slow releasing relays R6 and R8 are energized over their respective stick circuits, and relay R7 is energized over its stick circuit. Also, the operating circuit for signal S is open and signal S 50 does not operate.

55 The governing of the highway crossing signal S by the control apparatus may be understood from a description of the operation of the apparatus in response to an east-bound train approaching the highway.

60 The actuation of track instrument C1 by the passing train deenergizes relay R1, which opens front contact 6 and deenergizes relay R7. Relay R7 opens front contact 7, and closes back contact 13 which completes the circuit for signal S and signal S is placed in operation.

65 Relay R1 also opens front contact 2 and relay R6 deenergizes, opening front contact 4 and closing back contacts 10 and 14 at the end of its slow release period. This slow action permits front contact 7 of relay R7 to open before front contact 6 of relay R1 is shunted by back contact 10 of relay R6.

70 The actuation of track instrument C2 by the passing train deenergizes relay R2 which opens front contact 3.

75 When the train completely passes track instrument C1, relay R1 reenergizes and picks up to close its front contacts 2 and 6. Signal S

5 still operates because the stick circuit for relay R7 is open at front contact 7 of relay R7, and the pick-up circuit for relay R7 is open at back contact 12 of relay R3. When the train completely passes track instrument C2, relay R2 re-energizes and closes front contact 3 which completes the heating circuit for time element relay TE1. The heating of element 19 for a time period (10 seconds, for example) closes contact 5 and relay R6 reenergizes. When this happens, back contact 10 opens to remove the shunt across front contact 6 of relay R1 in the stick circuit of relay R1, and back contact 14 opens to open the heating circuit for time element relay TE1. Front contact 4 of relay R6 also closes to complete the stick circuit for relay R6, which holds the relay energized after contact 5 of time element device TE1 opens to break the pick-up circuit for relay R6 upon cooling of element 19 of time element device TE1.

10 When the train reaches track instrument C3, relay R3 deenergizes and closes back contact 12 which completes the pick-up circuit for relay R7 as previously traced. Relay R7 picks up and opens back contact 13 which stops the 15 operation of signal S. Moreover, the closing of front contact 7 of relay R7 completes the stick circuit for relay R7, which holds the relay energized after back contact 12 has been opened by the reenergizing of relay R3. Relay R3 re-energizes after the train completely passes track instrument C3.

20 The train in receding from the highway intersection actuates track instrument C4, which in turn deenergizes relay R4. The release of relay R4 opens front contact 15 to break the stick circuit for relay R8. At the end of its slow release period, relay R8 becomes deenergized, thereby opening front contact 16 and closing back contacts 11 and 17. The train in passing 25 track instrument C5 actuates the instrument, and deenergizes relay R5 to open front contacts 18 and 9. The stick circuit for relay R7 is not opened at front contact 9 of relay R5 because back contact 11 of relay R8 provides a 30 shunt path around front contact 9 of relay R5. From this, it can be seen that the distance between track instruments C4 and C5 may have any convenient value which permits the actuation of track instrument C4, the deenergization 35 of relays R4 and R8, and the closing of back contact 11 of relay R8 prior to the actuation by a train moving at maximum speed of track instrument C5, and the consequent deenergization 40 of relay R5 and the opening of front contact 9. 45 For example, assuming a maximum speed of 90 miles per hour, or 132 feet per second, and a release period for the slow release relays of the order of three-quarters of a second, during 50 which period a train will travel 99 feet, then the distance between track instruments C4 and C5 should be at least 100 feet. It follows that, with the apparatus proportioned in the manner just described, the relay R8 functions as a directional relay for preventing the track instruments C4 and C5 from governing the controlling means for signal S when actuated by a train receding from the intersection.

55 When the train completely passes track instrument C4, relay R4 reenergizes to close front contact 15. When the train completely passes track instrument C5, relay R5 reenergizes to close front contact 9, which reestablishes the normal stick circuit for relay R7. Front contact 18 of relay 60

R5 also closes, which completes a heating circuit for time element relay TE2, similar to that traced above for relay TE1. Element 20 heats, and, at the expiration of a time period, contact 21 of time element relay TE2 closes, completing the pick-up circuit for relay R8. Relay R8 energizes, back contact 11 opens to remove the shunt across front contact 9 of relay R5, and front contact 16 closes to complete the stick circuit for relay R8. This stick circuit holds relay R8 energized when contact 21 opens after heating element 20 of time element relay TE2 cools.

Thus, it can be seen that the apparatus operates the signal when a train approaches the intersection, and automatically terminates the operation of the signal when the train reaches the intersection.

The apparatus operates in a similar manner for a train approaching the highway in the opposite direction, which may be readily understood by reference to the drawing, without tracing the operation in detail.

The apparatus as here disclosed is simple and reliable, and requires no track circuits. As a result, a reliable highway crossing signal control may be effected without the necessity for breaking into a rail section or insulating a portion of the rails, and the positions of the track instruments can readily be changed if traffic conditions upon the intersection necessitates such change.

Although I have described and illustrated only one form of apparatus embodying my invention, it is to be understood that various changes and modifications may be made therein within the scope of the appended claims without departing from the spirit and scope of my invention.

Having thus described my invention, what I claim is:

40. 1. In combination, a stretch of railway track intersected by a highway, a highway crossing signal located adjacent the intersection, a first track instrument associated with the stretch at a selected point to one side of the intersection, a first normally energized relay controlled by said first track instrument, operating means governed by a front contact of said first normally energized relay and effective when a train operating in a first direction over said stretch actuates said first instrument to deenergize said first normally energized relay for operating the highway crossing signal, a second track instrument associated with the stretch at a selected point on the same side and nearer the intersection than the first track instrument, a second normally energized relay controlled by said second track instrument, a slow releasing relay normally energized over front contacts of said first and said second normally energized relays, and means including a back contact of said slow releasing relay to prevent said front contact of said first track instrument from governing said operating means.

65. 2. In combination, a stretch of railway track intersected by a highway, a highway crossing signal located adjacent the intersection, a first track instrument associated with the stretch at a selected point to one side of the intersection, a first normally energized relay controlled by said first track instrument, controlling means including a front contact of said first normally energized relay and effective when a train operating over said stretch in a direction to approach the intersection actuates said first

instrument for initiating the operation of the highway crossing signal, a second track instrument associated with the stretch at a selected point between the first track contactor instrument and the intersection, a second normally energized relay controlled by said second track instrument, a normally energized slow releasing stick relay, a stick circuit for said stick relay including front contacts of said first and said second normally energized relays in series, a time element device controlled by front contacts of said first and said second normally energized relays and a back contact of said slow releasing stick relay, a pick-up circuit for said stick relay including front contacts of said first and said second normally energized relays in series and a contact of said time element device, and means including a back contact of said stick relay and effective when a train operating over said stretch in the opposite direction actuates said second instrument to prevent said controlling means from initiating the operation of said signal.

3. In combination, a stretch of railway track intersected by a highway, a highway crossing signal located adjacent the intersection, a first track instrument associated with the stretch at a selected point to one side of the intersection, a first normally energized relay controlled by said first track instrument, a normally energized stick relay, a stick circuit for said normally energized stick relay including a front contact of said first normally energized relay, operating means including a back contact of said normally energized stick relay for operating the highway crossing signal, a second track instrument associated with the stretch at a selected point on the same side and nearer the intersection than said first track instrument, a second normally energized relay controlled by said second track instrument, a normally energized slow releasing stick relay, a stick circuit for said slow releasing stick relay including front contacts of said first and said second normally energized relays in series, a time element device controlled by front contacts of said first and said second normally energized relays and a back contact of said slow releasing stick relay, a pick-up circuit for said slow releasing stick relay including front contacts of said first and said second normally energized relays and a contact controlled by said time element device, and means including a back contact of said slow releasing stick relay to prevent said operating means from operating said signal when a train recedes from the intersection.

4. In combination, a stretch of railway track intersected by a highway, a highway crossing signal located adjacent the intersection, a first track instrument associated with the stretch at a selected point to one side of the intersection, a first normally energized relay controlled by said first track instrument, a normally energized stick relay, a stick circuit for said normally energized stick relay including a front contact of said first normally energized relay, operating means including a back contact of said stick relay for operating the highway crossing signal, a second track instrument associated with the stretch at a selected point on the same side and nearer the intersection than said first track instrument, a second normally energized relay controlled by said second track instrument, a normally energized slow releasing relay controlled by front contacts of said first and said second normally energized relay in series, directional means including a back contact of said slow releasing

relay to prevent said operating means from operating said signal when a train recedes from the intersection, a third track instrument located adjacent the intersection, a third normally energized relay controlled by said third track instrument, and means governed by a back contact of said third normally energized relay for stopping the operation of the highway crossing signal.

5. In combination, a stretch of railway track 10 intersected by a highway, a highway crossing signal located at the intersection, a first track instrument associated with the stretch at a selected point to one side of the intersection, a first relay governed by said first instrument, operating 15 means for operating said signal governed by said first relay and operative when a train approaching the intersection actuates said first instrument, a second track instrument associated with the stretch intermediate said first relay and the 20 intersection, a second relay governed by said second instrument, a directional relay governed by said first and said second relays, and means governed by said directional relay operative when

a train receding from the intersection actuates said second instrument for rendering said first relay ineffective to govern said operating means.

6. In combination with a stretch of railway track intersected by a highway and provided with a highway crossing signal located adjacent the intersection, a first track instrument associated with the stretch to one side of the intersection, operating means governed by said first instrument and effective when a train operating 10 in a first direction over said stretch actuates said first instrument for initiating the operation of said signal, a second track instrument associated with the stretch intermediate said first instrument and the intersection, a slow acting relay 15 controlled jointly by said first and second track instruments, and means governed by said slow acting relay and effective when a train actuates said second instrument prior to actuating said first instrument for preventing said first instrument from governing said operating means.

RONALD A. McCANN.
